UNITED STATES PATENT OFFICE

111,869

DESIGN FOR A CORN POPPING MACHINE

Irven H. Wilsey, Chicago, Ill.

Application February 18, 1938, Serial No. 75,224

Term of patent 7 years

To all whom it may concern:

Be it known that I, Irven H. Wilsey, a citizen of the United States, residing at Chicago, in the county of Cook and State of Illinois, have invented a new, original, and ornamental Design for Corn Popping Machines, of which the following is a specification, reference being had to the accompanying drawing, forming part thereof.

The single figure of the drawing is a front perspective view of the corn popping machine showing my device.

I claim:

The ornamental design for a corn popping machine, as shown.

IRVEN H. WILSEY.
